(57) **CLAIM**

The ornamental design for a skateboard shaped switchplate cover, as shown and described.

DESCRIPTION

FIG. 1 is a perspective view of a skateboard shaped switchplate cover showing my new design;

FIG. 2 is a top plan view thereof;

FIG. 3 is a front elevational view; the back elevational view being a mirror image thereof;

FIG. 4 is a left side elevational view thereof, the right side being a mirror image thereof; and,

FIG. 5 is a bottom plan view thereof.

The broken line showing of the screw holes, switch opening, and rear portion of the claim is included for the purpose of illustrating portions of the skateboard shaped switchplate cover and forms no part of the claimed design.
